UNITED STATES PATENT OFFICE.

HAROLD T. SMITH, OF WILLIS, KANSAS, ASSIGNOR OF ONE-HALF TO BENJAMIN L. CORNELIUS, OF NICKERSON, KANSAS.

OIL-BURNER.

1,096,063.

Specification of Letters Patent. Patented May 12, 1914.

Application filed July 13, 1910. Serial No. 572,400.

To all whom it may concern:

Be it known that I, HAROLD T. SMITH, a citizen of the United States, residing at Willis, in the county of Brown and State of Kansas, have invented certain new and useful Improvements in Oil-Burners, of which the following is a specification.

This invention relates to liquid fuel burners and my object is to produce a device of 10 this character which will operate efficiently and reliably and is of simple, strong, durable and cheap construction.

With this object in view the invention consists in certain novel and peculiar features 15 of construction and organization as herein-after described and claimed; and in order that it may be fully understood reference is to be had to the accompanying drawing, in which—

20 Figure 1, is a central longitudinal section of a burner embodying my invention. Fig. 2, is a section on the line II—II of Fig. 1. Fig. 3, is a section on the line III—III of Fig. 1. Fig. 4, is a section on the line 25 IV—IV of Fig. 2.

In the said drawing, 1 indicates the body of the burner, the same being of elongated form and hollow to provide an oil chamber 2 contracted at its front end to produce the 30 neck 3. Cast integral with the body and communicating with the interior thereof and extending forwardly from the neck is a hollow nozzle 4. Opposite walls 5 of the nozzle diverge forwardly and laterally, and the remaining walls 6 converge and nearly meet 35 at their front ends, so that at the tip of the burner the combustible mixture, hereinafter referred to, shall escape in a wide and shallow jet.

40 7 indicates a threaded boss communicating with the rear end of chamber 2, and 8 an oil supply pipe screwed into the threaded boss.

45 9 is a projection cast integral with the body 1 and provided with a passage 10 communicating with a threaded boss 11 at the opposite side of the body from boss 7, and screwed into the boss 11 is a steam supply pipe 12. The projection 9 is also cast with a 50 longitudinal passage 13 communicating with a threaded opening 14, closed by a plug 15.

Extending longitudinally within and of substantially the same length as the body, is a tubular steam nozzle 16 communicating at its rear end with passage 10 and adapted to 55 discharge steam through the neck 3 into the nozzle 4, said nozzle 16 being produced by the introduction of a boring tool through passage 13 before the plug 15 is secured in place.

60 In practice steam enters the burner through pipe 12 and is discharged from nozzle 16 into the nozzle 4 and thus tends to create a vacuum and to effect the injection of oil through pipe 8 into chamber 2 and 65 thence into the nozzle 4, where it is thoroughly mixed with the steam, the mixture being thorough because the form of the nozzle 4 compels the oil to spread out into a comparatively thin film and thus permit the 70 steam to come into contact with every part of it.

With a burner of this character where the steam effects the injection of the oil into the nozzle, no means for feeding the oil, other 75 than gravity need be resorted to, nor in fact is it necessary to utilize gravity if the steam is under high pressure.

While the appliance is described as used in connection with steam and oil, it is to be understood that air may be employed as a substitute for the steam.

80 From the above description it will be apparent that I have produced an oil burner embodying the features of advantage 85 enumerated. I wish it to be understood that I reserve the right to make all changes falling within the spirit and scope of the appended claim.

Having thus described the invention what 90 I claim as new and desire to secure by Letters Patent, is:—

95 An oil burner, comprising a casing having a cylindrical portion and a flattened nozzle portion connected together by a constricted neck portion, said nozzle portion widening gradually toward its mouth and the walls of the nozzle being gradually tapered about said mouth, a pair of threaded bosses forming air inlet and steam inlet openings respectively, at diametrically opposite points 100 on the rear end of said cylindrical portion

of the casing, a steam inlet chamber formed about said steam inlet opening and provided with a steam nozzle extending axially through said cylindrical portion to said constricted neck portion, the rear end of said cylindrical portion of the casing having an opening in communication with said steam chamber and in line with said steam nozzle,

and a plug fitting removably in said opening.

In testimony whereof I affix my signature, in the presence of two witnesses.

HAROLD T. SMITH.
